UNITED STATES PATENT OFFICE.

HENRI HERRMANN, OF PARIS, FRANCE.

METHOD OF MANUFACTURING ELECTRICAL COLLECTORS, COMMUTATORS, CONTROLLERS, OR INTERRUPTERS, OR EQUIVALENT DEVICES.

1,426,293.

Specification of Letters Patent. Patented Aug. 15, 1922.

Application filed July 14, 1920. Serial No. 396,287.

To all whom it may concern:

Be it known that I, HENRI HERRMANN, a citizen of the Republic of France, residing at Paris, Seine, France, have invented a new and useful Method of Manufacturing Electrical Collectors, Commutators, Controllers, or Interrupters, or Equivalent Devices, of which the following is a specification.

The object of my present invention is to provide method of manufacturing electrical collectors, commutators, controllers, or interrupters, or equivalent devices, which can be readily and economically manufactured by moulding.

According to my invention the insulating matrix of the device is composed of insulating material shaped under sufficient heat in a mould in which the conducting strips, or contact pieces, (suitably spaced in accordance with the positions they are to occupy) and, if necessary, a hub and means, such as ties, or corrugations, for securing the parts together, have previously been inserted.

I will describe my invention with reference to the accompanying drawing, as, from this, its nature and how it may be performed will be understood. Figures 1 and 2 show in longitudinal section and transverse section respectively, a device made in accordance with my invention which I will presume to be a collector, or commutator, for a direct-current dynamo. Figure 3 shows a cylinder, or tube, in which openings have been cut, this cylinder being for use in the formation of the said device. Figure 4 is a vertical section of a mould for use in making the devices.

The device shown in Figures 1 and 2 consists of, or comprises, a hub *a* provided externally with corrugations, or the like, (such as the grooves *b*) and of a series of conducting strips, or contact pieces, *c* (of copper for example) embedded in the moulded insulating material *d*, the said strips, or pieces, being secured to the material *d* by any suitable means such for example as the curved pins *e*, embedded in the material *d*.

The moulding of the device may be effected in the following manner. A metal cylinder or tube *f*, of suitable thickness and of a length slightly exceeding that of the device, is provided with a series of gaps or longitudinal slots *g*. The length of each gap is the same as the length of the finished device and the width as indicated at *l* is equal to

the width of the spaces between the conducting strips of contact pieces *c*.

The widths *l* are somewhat exaggerated in Figures 2 and 3 to make the drawing clearer.

This cylinder, or tube, *f* is inserted in a metal mould (say a steel mould for instance) consisting of a base *h*, on which is mounted a body-part *i*. The hub *a*, accurately centred by means of a boss as shown, is then inserted in the mold, and inside this hub is placed the small end of a mandrel *k*, the shoulder *r* of which rests on the end of the hub *a*.

The cylinder, or tube, *f* is inserted in the body-part *i* so that the plain, or unslotted, lower end *n* below the gaps *g* fits into the annular space between the projecting upper portion of the base *h* and the inner wall of the body-part *i*, a centering ring *o* being put in position on top of the cylinder, or tube, *f*.

Into the space between the hub *a* and the cylinder *f* is introduced an insulating mixture (such, for example, as powdered mica and a binding medium) up to a level somewhat higher than the upper end of the hub, and an annular piston *g* is passed over the mandrel *k*. The mould thus equipped, is heated sufficiently to bring the insulating mixture to a pasty, or viscous, condition and pressure is then applied to the annular piston *g*. The mould and its contents are then allowed to cool down and, after a time, when the mixture has become sufficiently set, (which time varies with the nature of the insulating material employed), the moulded device is removed from the mould and the upper ends are trimmed off and the gaps *g* are extended through the lower end, the free ends of the strips can be connected with the coils of the armature, by riveting, or other suitable means and the device is then finished.

The method of manufacture hereinbefore explained can be applied to making any similar electrical devices such, for example, as commutators, interrupters, controllers, or the like, comprising metallic members which have to be separated by, or embedded in, insulating material.

What I claim is:—

1. The method of manufacturing a commutator, which comprises longitudinally slotting a metal cylinder between its ends to form a series of spaced strips, mounting the slotted cylinder in a cylindrical mould,

mounting a cylindrical hub concentrically within the slotted cylinder, and introducing heated insulating material between the cylinder and hub under sufficient pressure to compress the insulating material between the strips of the cylinder and against the mould.

2. The method of manufacturing a commutator, which comprises longitudinally slotting a metal cylinder between its ends to 10 form a series of spaced strips, mounting the slotted cylinder in a cylindrical mould, closing the unslotted lower end of the cylinder, mounting a cylindrical hub concentrically within the slotted cylinder, and introducing 15 heated insulating material between the cylinder and hub under sufficient pressure to compress the insulating material between the strips of cylinder and against the mould.
3. The method of manufacturing a commutator, which comprises longitudinally slotting a metal cylinder between its ends to 20 form a series of spaced contact strips, mounting the slotted cylinder in a cylindrical mould, closing the unslotted lower portion 25 of the cylinder, mounting a cylindrical hub concentrically within the slotted portion of the cylinder, closing the upper end of the

hub, introducing heated insulating material between the cylinder and hub throughout the slotted portion of the cylinder, and applying sufficient pressure to the insulating material to compress the same between the strips of the cylinder and against the mould. 30

4. The method of manufacturing a commutator which comprises longitudinally slotting a metal cylinder between its ends to 35 form a series of spaced contact strips, projecting a plurality of curved pins through the strips into the cylinder, mounting the latter in a cylindrical mould, embedding the 40 unslotted lower end of the cylinder in the end of the mould, mounting a cylindrical hub concentrically within the slotted portion of the cylinder, closing the upper end of the hub, introducing heated insulating material 45 between the hub and cylinder throughout the slotted portion of the latter, and applying sufficient pressure to the insulating material to pack the same around the pins and between the spaced contact strips. 50

In witness whereof, I have hereunto signed my name.

HENRI HERRMANN.
